(57) **CLAIM**

The ornamental design for a set-top box remote control, as shown and described.

DESCRIPTION

FIG. 1 is a top perspective view of a set-top box remote control showing my new design;

FIG. 2 is a top plan view thereof;

FIG. 3 is a side view thereof;

FIG. 4 is a bottom view thereof;

FIG. 5 is a front side view thereof; and,

FIG. 6 is a back side view thereof.

In the drawings, the broken lines depict environmental subject matter only and form no part of the claimed design. The dot-dash line surrounding the top surface represents the boundary of the claim.

In FIGS. 1 and 2, four buttons are lined for color.
